UNITED STATES PATENT OFFICE

HAROLD A. OSBORNE, OF LYNN, MASSACHUSETTS, ASSIGNOR TO UNITED SHOE MANUFACTURING CORPORATION, OF PATERSON, NEW JERSEY, A CORPORATION OF NEW JERSEY

ART OF MAKING SHOES

Application filed April 25, 1928. Serial No. 272,781.

This invention relates to improvements in the art of making shoes and is herein set forth with particular reference to the manufacture of shoes having special provision for supporting the metatarsal arch of the foot.

In a shoe of the special character indicated, the insole is formed with a bulge or protuberance so located and constructed as to lie beneath and provide support for the metatarsal arch of the foot. In the manufacture of such shoes it has been customary to mold the bulge in the insole before applying the insole to the last and thereafter to place the molded insole upon a last having in its bottom surface a cavity or depression corresponding in shape and location to the shape and location of the protuberance or bulge already formed in the insole so as to receive the bulge in a manner to avoid flattening it or altering its shape during the subsequent operations of making the shoe. It has been proposed to mold the bulge simultaneously with the molding of the rest of the insole to fit the transverse and longitudinal curvatures of the last bottom, and to employ for this purpose complementary dies or molds shaped to form a bulge of the desired contour and, in addition, to impart the usual surface contour to the rest of the insole. In making metatarsal arch supporting shoes commercially, however, it is necessary to have the arch supporting bulge properly located in all insoles irrespective of variations in size, width and style of insole and it is often desirable also, in different shoes of the same size, width and style, to provide different degrees of bulge to adapt the shoes for different degrees of foot arch or different peculiarities of foot structure. This would involve the use of a greater number of molds for a given run of sizes than would be required if the molds were adapted to perform only the usual sole molding operation, it being practicable and customary in the latter case to use the same mold for at least several different sizes and widths of soles. Consequently, the proposed method of molding the arch supporting bulge would be relatively expensive to carry out.

In view of the foregoing, one object of the present invention is to provide a relatively inexpensive method of making arch supporting insoles, or shoes in which such insoles are incorporated, as well as to provide a method of this character which, in practice, will insure that the arch supporting bulge or protuberance will be properly shaped and accurately located in each individual insole or shoe.

With this object in view the invention, in one aspect, consists in molding an insole to fit the contour of the bottom of a normal last, and thereafter displacing the insole flatwise to form a metatarsal arch supporting bulge therein while holding the sole margin against edgewise displacement at opposite sides of the area where the bulge is being formed. As illustrated, the insole is placed upon a last having a cavity in its bottom surface, and thereafter the insole is forced into said cavity to form an arch supporting protuberance on the insole. The cavity in the illustrated last bottom is located to correspond to the location of the metatarsal area of the foot and is shaped according to the contour desired to be imparted to the protuberance on the insole, thus positively insuring that the protuberance will be accurately located and properly shaped in each individual sole.

As well known in the art, it is frequently desirable to have an insole molded to insure that it will fit better upon the last and, in accordance with the present method as herein exemplified, the insole, before the arch supporting bulge is formed therein, is molded between complementary dies or molds shaped to impart to the insole a surface contour corresponding to that of the last bottom except at that portion where the cavity is formed. Preferably after the insole has been placed upon the last, an upper is assembled with the insole and the upper is lasted and its margin is secured to the insole. In the drawings the present method is illustrated as being carried out in connection with the manufacture of welt shoes and accordingly there is shown an insole having a sewing rib to which the upper is secured by inseam stitches in the usual way. However, the in-

vention may also be useful in connection with the manufacture of other kinds of shoes as, for example, McKay sewed shoes in which case the upper will be secured to the insole by means of lasting tacks or staples. When an insole has been inseamed or otherwise permanently secured to a lasted upper, before the arch supporting bulge is formed, the marginal portions of the insole will be positively held so that they cannot move inwardly while the insole is being forced into the cavity in the last. Consequently, the material of the insole will be actually stretched by the bulge-forming pressure and the process of forming the bulge will not result in any narrowing of the sole at the shank or in otherwise altering the shape or marginal contour of the sole. Where the sole material is actually stretched, as above described, and as distinguished from merely being shaped by the usual molding operation, the fibers of the leather will be permanently distorted in such fashion that the bulge will tend to retain indefinitely the shape initially imparted to it.

25 The foregoing and other aspects of the invention will be set forth in the following description and pointed out in the appended claims.

The invention will be explained with reference to the accompanying drawings, in which

30 Fig. 1 is a view, partially in side elevation and partially in section, of a pair of complementary sole molds illustrating their mode of operation upon a sole;

35 Figs. 2 and 3 are cross-sectional views taken respectively along the lines II—II and III—III of Fig. 1;

40 Fig. 4 is a perspective view showing the grain or foot-engaging surface of an insole as it appears after the insole has been shaped by the molds shown in Figs. 1 to 3;

45 Fig. 5 is a perspective view of a molded insole illustrating conventionally the manner of applying adhesive to the channel lips before the lips are turned;

50 Fig. 6 is a view showing, in side elevation, the operating instrumentalities of an insole lip turning machine and illustrating the operation of turning and setting the channel lips;

55 Fig. 7 is a perspective view of a molded insole showing the flesh or lipped side of the insole as it appears after the lips have been turned and cemented together in upright position to form a sewing rib;

60 Fig. 8 is a perspective view of a last having a cavity in its bottom face adapted to form a metatarsal arch supporting bulge in an insole;

65 Fig. 9 is a perspective view of a last like that shown in Fig. 8 having a molded insole laid thereon;

Fig. 10 is a longitudinal sectional view of a shoe as it appears after the insole and the

upper have been united by inseam stitches, the shoe being mounted on a last similar to that shown in Figs. 8 and 9;

70 Fig. 11 is a view similar to Fig. 10 but illustrating the operation of peening the insole into the cavity in the last bottom to form the metatarsal arch supporting bulge;

75 Figs. 12 and 13 are cross-sectional views taken respectively along the lines XII—XII of Fig. 10 and XIII—XIII of Fig. 11;

80 Figs. 14 and 15 are perspective views of a shoe mounted on a last illustrating different stages in the manufacture of the shoe prior to the attachment of the outsole;

85 Fig. 16 is a longitudinal sectional view of a portion of the bottom of a finished shoe in the vicinity of the arch supporting bulge; and

90 Fig. 17 is a cross-sectional view through the same portion of the shoe as that shown in Fig. 16.

95 In carrying out the method of the present invention as herein illustrated with reference to the manufacture of welt shoes, an insole

2 is first channeled in the usual manner to provide inner and outer channel lips 4 and 6. Before the channel lips are raised or turned, the insole is moistened or tempered and is then molded in a sole molding machine between complementary dies or molds 8 and 10 (Figs. 1 to 3). The mold members 8 and

10 are shaped to impart to the insole the longitudinal and transverse curvatures shown in Figs. 1 to 4. The sole is thus formed with a surface contour (see Fig. 4) similar to that customarily provided in molded insoles wherein no special provision is made for supporting the metatarsal arch.

99 As shown, the shank portion of the insole is more or less abruptly offset from the plane of the forepart and is made transversely concave and longitudinally convex on its upper or foot-engaging side, the more closely to conform to the general shape of the bottom of a foot without, however, at this stage in its manufacture, having any upward bulge or protuberance in that portion which is to underlie the metatarsal arch.

105 Fig. 4 is a perspective view showing the grain or foot-engaging surface of an insole as it appears after the insole has been shaped by the molds shown in Figs. 1 to 3;

110 Fig. 5 is a perspective view of a molded insole illustrating conventionally the manner of applying adhesive to the channel lips before the lips are turned;

115 Fig. 6 is a view showing, in side elevation, the operating instrumentalities of an insole lip turning machine and illustrating the operation of turning and setting the channel lips;

120 Fig. 7 is a perspective view of a molded insole showing the flesh or lipped side of the insole as it appears after the lips have been turned and cemented together in upright position to form a sewing rib;

125 Fig. 8 is a perspective view of a last having a cavity in its bottom face adapted to form a metatarsal arch supporting bulge in an insole;

130 Fig. 9 is a perspective view of a last like that shown in Fig. 8 having a molded insole laid thereon;

and pressing them together may conveniently be performed by means of a lip turning machine such as that disclosed in United States Letters Patent No. 1,576,748, granted March 16, 1926, on application of A. E. Johnson. In Fig. 6 some of the operating instrumentalities of this patented machine have been shown in operation upon the insole 2, the lip setting rolls being indicated at 16 and 18, and the feed roll at 20. If desired, the sewing rib 14 may be reinforced by means of canvas or other material (not shown) which material may be applied in any well-known manner.

The insole is next laid upon the bottom of a last, such as the last 22 shown in Figs. 8, 9 and 10, this last having a cavity 24 formed in its bottom surface near the junction of the shank and forepart of the last.

The depressed portion of the last bottom within the cavity 24 is adapted to serve as a form to determine the contour of a metatarsal arch supporting bulge or protuberance which is to be formed in the insole. To this end, the cavity 24 is preferably formed as shown in the drawings inasmuch as an insole bulge of a corresponding shape has been found best adapted to support the metatarsal arch of the average foot. As shown in Fig. 8 the cavity 24 is preferably bounded by a sharply defined continuous line 25 where the depressed surface somewhat abruptly terminates. This construction insures that the bulge in the insole will have a similar clearly defined line marking its junction with the adjacent surface of the insoles and thus accentuate the bulge, making it readily noticeable as a distinctive feature of the shoe without disadvantageously affecting the arch supporting properties of the bulge. The particular contour and marginal shape of the bulge in the insole, and consequently of the cavity in the last, may of course be varied as found to be expedient without departing from the spirit of the invention. In practice it may be found desirable to vary both the shape and the size of the bulge according to the particular style of last employed, and not only this but for a given style of last it may be desirable to provide different degrees of bulge to adapt the shoes for different degrees of foot arch or different peculiarities of foot structure. In this connection it may also be noted that if the bulge were to be molded simultaneously with the molding of the rest of the sole as heretofore proposed, not only might it be desirable or necessary to employ a different mold for each size, width and style of last but also a plurality of molds might be required to provide for the above-mentioned variations in degree or shape of bulge in a given style of shoe.

After being laid in proper position upon the last the insole is secured in place as by means of tacks 26. An upper 28 is then assembled with the insole on the last and lasted

over the margin of the insole in the usual way. Next, the upper is permanently secured to the insole by the usual inseaming operation. At this stage in its manufacture the shoe appears as shown in Fig. 10, the inseam stitching being indicated at 30 as securing the upper 28, together with a welt 32, to the sewing rib 14 of the insole. As a result of the lasting and inseaming operations not only is the sole held firmly in place upon the last but, being stitched to the tightly stretched upper, the sole is firmly and positively held in such a manner that it can not be shifted edgewise nor the sole margins displaced by any action which may subsequently be performed upon the sole.

At this stage in the manufacture of the shoe the metatarsal arch supporting bulge is formed by forcing the portion of the insole overlying the cavity 24 into the cavity 24 and preferably into intimate engagement with the walls of the cavity. As illustrated, the forcing of the insole into the cavity 24 may be effected manually by means of blows delivered by a hammer such as the peening hammer shown at 34 in Fig. 11, so that the insole material is actually beaten or pounded into the cavity 24. When acted upon in this manner the insole material is caused accurately to conform to the contour of the walls of the cavity 24. Moreover, since the sole margins are positively held against edgewise shifting movement, none of the sole material outside the boundary of the cavity in the last bottom can be drawn into the cavity by the bulge forming pressure to provide excess material to produce the bulge. Consequently the bulge will be produced by actual stretching of the sole material. Such stretching causes permanent distortion of the fibers of the leather with the result that the shape initially imparted to the bulge will tend to be indefinitely retained. The manner in which the insole is stretched by the action of the hammer 34 will be apparent from a comparison of Figs. 12 and 13. In Fig. 12 the insole is shown as bridging the cavity 24, whereas in Fig. 13 the same portion of the insole is shown as being conformed to the walls of the cavity by the peening action of the hammer 34 so as to form a substantial bulge or protuberance 36.

By using the wall of the cavity in the last to determine the shape of the arch supporting bulge a substantial saving in cost of manufacture can be effected inasmuch as the molds which shape the rest of the insole do not have to be provided with additional complement portions for producing the bulge and a smaller number of molds are necessary for molding a run of insoles without bulges than for molding the same run of insoles having bulges. It will be understood that even when the bulges are formed by the sole molds the lasts have to be provided with

cavities to receive these bulges while the shoes are being made. Accordingly the formation of the cavities in the lasts used in the practice of the present method does not add to the expense of making the soles or the shoes. Moreover, by utilizing the cavity in the last for the purpose of forming the bulge after the insole has been secured to the last, the location of the bulge in the shoe is positively and accurately determined.

In making shoes under commercial conditions in accordance with the herein-described method various operations will be performed upon a quantity of soles. The shoe's 15 will be made up in case lots and a quantity of shoe parts or partially completed shoes will be subjected in turn to each successive step of the method. As a result, the insoles may become more or less out of temper before it becomes time for the arch supporting bulge to be formed therein. Consequently, for practical purposes it may often be desirable to moisten that portion of the insole where the bulge is to be formed immediately before it is forced into the cavity in the last. This local moistening or tempering of the insole may conveniently be performed by means of a wet sponge 38 as shown in Fig. 10.

After the bulge 36 has been produced on the insole the depression formed beneath the bulge at the outer side of the insole is filled depthwise of the depression by means of a filler piece 40 of any suitable material. This 35 filler piece may be shaped as shown in Fig. 14 or it may be made of any convenient shape, its purpose being to support the bulge 36 against the pressure of the foot while the shoe is being worn. The filler piece 40 may be held in place by any other suitable means such as cement. After the filler piece 40 has been secured in place, the space inside of the insole is filled as by means of the usual filling material 42 (Fig. 15) and a shank 45 stiffener 44 is applied, preferably with the forward extremity of the stiffener overlying the filler piece 40. As shown, the rear end only of the shank stiffener is secured by tacks 46 to the innersole, the forward portion of the stiffener being left unscrewed so as to impart resilience to the shank portion of the shoe. The filler piece 40 is intended substantially to fill the space heightwise of the shoe between the shank stiffener and the 55 insole to provide a firm support for the bulge 36. After the shank stiffener has been applied the shoe is ready to have the outsole secured to the welt and the shoe may then be finished in the usual manner.

60 While the invention has been disclosed herein in connection with the manufacture of welt shoes it is not necessarily so restricted in its application but as hereinbefore indicated may also be useful in connection with 65 the manufacture of other kinds of shoes.

Having described my invention, what I claim as new and desire to secure by Letters Patent of the United States is:

1. That improvement in methods of making insoles for arch support shoes which comprises molding an insole to fit the contour of the bottom of a normal last, and thereafter displacing the insole flatwise to form a metatarsal arch supporting bulge therein while holding the sole margin against edgewise displacement at opposite sides of the area where the bulge is being formed. 70

2. That improvement in methods of making shoes which comprises placing an insole upon a last having a cavity in its bottom face, assembling an upper with the insole on the last, lasting the upper and securing its margin to the insole, forcing the insole into the cavity in the last bottom to form an arch supporting bulge on the inside of the shoe, and laying an outsole and securing it to the shoe in the usual manner. 80

3. That improvement in methods of making shoes which comprises placing an insole upon a last having a cavity in its bottom face, assembling an upper with the insole on the last, lasting the upper and securing its margin to the insole, and thereafter forcing the insole into the cavity in the last bottom to form a bulge on the inside of the shoe, assembling within the cavity in the outer face of the insole filler material for supporting said bulge, and then laying and securing an outsole to the shoe in the usual manner. 90

4. That improvement in methods of making shoes which comprises molding an insole to impart thereto the usual transverse and longitudinal curvatures, placing the molded insole upon a last provided with a cavity in its bottom face, assembling an upper upon the last, lasting and securing the margin of the upper to the insole, thereafter beating the insole into the cavity in the last to form a bulge or projection on the inside of the shoe, filling the cavity in the outer face of the insole, and then laying and securing the outsole to the shoe in the usual manner. 100

5. That improvement in methods of making shoes which comprises placing an insole upon a last having a cavity in its bottom face, assembling an upper upon the last, lasting the upper and securing its margin to the insole, and thereafter pressing the insole into the cavity in the last bottom to form a bulge on the foot engaging surface of the insole and a corresponding depression in the opposite side of the insole, and inserting a filler within said depression to prevent collapse of the bulge under pressure of a foot in the shoe. 110

6. That improvement in methods of making shoes which comprises forming a sewing rib upon an insole, placing the insole upon a last having a cavity in its bottom face, assembling an upper upon the last, lasting and in- 120

seaming the margin of the upper to the insole, and thereafter pressing the insole into the cavity in the last bottom to form a bulge upon the foot engaging side of the insole and a 5 corresponding depression in the opposite side of the insole.

7. That improvement in methods of making shoes which comprises channeling an insole, molding the insole before the channel 10 lips are raised to impart thereto the usual transverse and longitudinal contours of a last bottom, raising and setting the channel lips to form a sewing rib, attaching the insole to a last having a cavity or depression in 15 its bottom face located in a position to correspond with the metatarsal area of the foot, assembling an upper upon the last, lasting and inseaming the upper, thereafter beating the material of the insole into the cavity in 20 the last, thus forming a depression in one side of the insole and a corresponding bulge upon the opposite side of the insole, filling the space inside the inseam including said depression in the insole, laying the outsole, and completing the shoe in the usual manner.

8. That improvement in methods of making shoes which consists in channeling an insole, molding the insole to impart thereto the transverse and longitudinal contours of a last bottom, thereafter raising and setting the channel lips to form a sewing rib, attaching the insole to a last having a cavity in its bottom face located in the vicinity of the ball line of the last, assembling an upper 30 upon the last, lasting the upper, performing the inseaming operation, thereafter shaping the material of the insole into the cavity in the last bottom, thus forming a depression in one side of the insole and a corresponding 35 bulge upon the opposite side of the insole, filling said depression at least partially with solid filling material, applying a steel shank stiffener to the shoe with the forward end of the stiffener overlying the filled depression 40 in the insole, filling the bottom of the shoe, laying the outsole, and completing the shoe in the usual manner.

9. That improvement in methods of making shoes which consists in placing an insole 50 upon a last provided with a cavity in its bottom face, assembling an upper upon the last, lasting and securing the margin of the upper to the insole, and thereafter moistening the portion of the insole overlying the cavity in the last and forcing the insole into the cavity of the last to form a bulge or projection on the inside of the shoe.

10. That improvement in methods of making insoles for arch support shoes which comprises molding an insole to impart thereto the usual transverse and longitudinal curvatures, placing the molded insole upon a form having a cavity shaped to form a metatarsal arch supporting bulge in the insole but otherwise conforming to the transverse and longi-

tudinal curvatures imparted to the insole, positively securing the lateral margins of the insole at opposite sides of said cavity against inward edgewise displacement, and, while the insole is so secured, forcing the 70 portion of the insole overlying said cavity into engagement with the walls of the cavity to form an arch supporting bulge in the insole without altering the edge contour of the sole margin.

In testimony whereof I have signed my name to this specification.

HAROLD A. OSBORNE.
